UNITED STATES PATENT OFFICE.

WALTER LAURENTIUS, OF BERLIN, GERMANY, ASSIGNOR TO GENERAL ELECTRIC COMPANY, A CORPORATION OF NEW YORK.

MULTIPLE RECEIVING DEVICE.

Application filed July 27, 1925, Serial No. 46,289, and in Germany August 1, 1924.

My present invention relates to a multiple receiving device for connecting radio head sets or loud speakers in series.

It is an object of my invention to provide 5 a simple and reliable means for connecting a plurality of receiving devices in series with each other and with a source of current supply.

A further object of my invention resides 10 in the means for normally short circuiting the pairs of jacks associated with the multiple receiving device, together with means for removing the short circuit from any pair of jacks when a receiver plug is inserted there- 15 in.

The novel features which I believe to be characteristic of my invention are set forth with particularity in the appended claims. My invention itself, however, both as to its 20 organization and method of operation will best be understood from the following specification taken in connection with the accompanying drawing in which Fig. 1 is a view partly in cross-section and partly in 25 elevation; Fig. 2 a plan view partly broken away; Fig. 3 is a wiring diagram of the multiple receiving device; and Fig. 4 is a detail view showing the circuit interrupting device associated with each pair of 30 jacks.

A plurality of pairs of jacks *a* and *b* are arranged radially in a multiple receiving device *C*, which may be constructed in any manner desired. Into jack *a* of each pair of 35 jacks there extend an insulating pin *d* which is fastened on a leaf spring *e* conductively connected to jack *b*. Leaf spring *e* makes contact with a second leaf spring *f* which is conductively connected to jack *a*. Consequently, the individual pairs of jacks are 40 short circuited and are connected in series by the contact device and the connections *g* which extend between adjacent pairs of jacks. When a plug connected to a head 45 set or loud speaker is introduced into a pair of jacks, the pin *d* associated with that pair of jacks is pressed outwardly so that the contact between the two leaf springs *e* and *f* of that pair is interrupted. The short circuit 50 connection between the two jacks *a* and *b* of the pair of jacks is thus eliminated so that the audio frequency current may flow 55 through the head set or similar device connected to the jacks. In other words, by introducing the head set plugs in the pair of

jacks, the individual head sets become automatically connected to the source of current supply, and thus may be connected to the multiple receiving device in any desired order.

Various modifications of my invention will readily suggest themselves to persons skilled in the art without departing from the scope of my invention as set forth in the appended claims.

What I claim as new and desire to secure by Letters Patent of the United States, is:—

1. In combination, a multiple receiving device comprising a plurality of pairs of 70 jacks, means normally short circuiting each of said pair of jacks, said means including a spring contact, and an insulating pin mounted on said contact and projecting into one of said jacks whereby the connection of 75 a receiving device to any one of said pairs of jacks removes the short circuit therefrom.

2. In combination, a multiple receiving device comprising a plurality of pairs of 80 jacks, means normally short circuiting each pair of jacks, said means including a plurality of spring contacts, and means for automatically removing said short circuit when a receiving device is connected to a pair of jacks, said means comprising an insulating pin connected to one of said contacts 85 and projecting into one of said jacks.

3. In combination, a multiple receiving device including a plurality of pairs of contacts, means normally short circuiting said 90 contacts, a movable insulating pin associated with each pair of contacts, and means whereby the connection of a receiving device to any one of said pairs of contacts actuates the pin associated with that pair of contacts 95 to remove the short circuit therefrom.

4. In combination, a circuit including a plurality of pairs of contacts normally connected in series, and means for opening the circuit between certain of said contacts and 100 for connecting a receiving device in that portion of the circuit, said means including a movable insulating pin connected to one of said contacts.

5. In combination, a pair of jacks, a pair 105 of contacts normally short circuiting said jacks, a pin associated with one of said contacts and projecting into one of said jacks, whereby said contacts may be opened when a plug is inserted in said pair of jacks.

6. In combination, a pair of jacks, a spring contact associated with one of said jacks and normally short circuiting said jacks, an insulating pin associated with said 5 spring contact and projecting through an opening into the other of said jacks whereby said contact may be actuated to open the short circuit when a plug is inserted in said jacks.
- 10 7. In combination, a pair of jacks, one of which has an opening in the side thereof, a
- spring contact connected to each of said jacks, said contacts being normally in engagement and serving to short circuit the jacks, a pin mounted on one of said contacts and extending through the opening in said one jack whereby said contacts may be opened when a plug is inserted in said one jack.

In witness whereof, I have hereunto set 20
my hand this 6th day of July, 1925.

WALTER LAURENTIUS.
